METHOD OF MANUFACTURING FASTENER
STRINGERS

Louis H. Morin and Davis Marinsky, New York,
N. Y., assignors to Whitehall Patents Corpora-
tion, New York, N. Y., a corporation of New
York

Application December 7, 1933, Serial No. 701,290

18 Claims. (CL 22—202)

This invention relates to the production of fastener stringers of what are known as separable fasteners, and particularly to a method of producing the stringers of fasteners of the class under consideration; and the object of the invention is to provide a method for forming devices of the class described which consists in casting or molding a link onto a core disposed between adjacent surfaces of die parts employed for forming the link as well as upon a mounting strip or strand positioned between said die parts; a further object being to provide a method which consists in intermittently casting successive links on the mounting member and further in casting the successive links on a core which is used as a means for feeding links and the mounting member through the machine and further as a means of ejecting the links from the dies and from which the links are stripped in the operation of spacing the links one from the other; a further object being to provide a method which includes the step of shearing or trimming the cast or molded link to remove the gate or other protruding body of the casting; a still further object being to provide a method which includes means for maintaining predetermined temperature to the casting or molding material employed as well as to heat the ejecting nozzle and the control of the temperature of such nozzle and still further, cooling the forming dies by the circulation of water therethrough and especially in the immediate ejection or discharge of the cooling water from the dies; and with these and other objects in view, the invention consists in a method of the class and for the purpose specified, which is more fully hereinafter described and claimed.

The invention described and claimed herein constitutes a continuation in part of the method described and claimed in application Serial Number 661,099, filed March 16, 1933 in which application the broad method claims of the invention have been drawn and is fully disclosed in the following specification, of which the accompanying drawings from a part, in which the separate parts of the improvement are designated by suitable reference characters in each of the views, and in which:

Fig. 1 is a diagrammatic sectional view illustrating parts of the apparatus for carrying the invention into effect.

Fig. 2 is a view similar to Fig. 1 showing a modification.

Fig. 3 is a sectional plan view on the line 3—3

of Fig. 1 on an enlarged scale with parts of the construction broken away and omitted.

Fig. 4 is a view similar to Fig. 3 with parts in a different position and with parts omitted.

Fig. 5 is a view similar to Fig. 1 showing only a part of the construction and indicating another step in the operation of the machine.

Fig. 6 is a plan view of the structure shown in Fig. 5 showing the position of the parts prior to removing the core from a finished casting.

Fig. 7 is a face view of the structure shown in Fig. 6 with parts broken away and in section.

Fig. 8 is a view similar to Fig. 5 showing the step of trimming a preformed casting and the operation of forming another casting; and,

Fig. 9 is a face view of a part of a stringer made according to the method with part of the construction broken away.

For the purpose of diagrammatically illustrating the invention, we have shown in Fig. 1 of the drawings parts of an apparatus more completely shown and described in application Serial Number 691,934, heretofore referred to. The elements of the apparatus performing the steps of the method are diagrammatically illustrated for the sake of clear understanding.

In said figure, 10 represents a casing in which is disposed a pot or container 11 for the molding material 12 to be used in forming the moldings or castings. Where required, the material 12 is maintained at the desired temperature by electrical or other suitable heating means 13. The temperature is automatically controlled by a temperature control tube or device 14 in circuit with a pyrometer 15, the latter being also in circuit with the electric heating means 13. The pot or container 11 includes a goose-neck discharge 11a with which is coupled a discharge nozzle 16 and the bottom of the goose-neck 11a communicates with a plunger cylinder 11b in which is disposed a plunger 17 for forcing the material 12 out through the nozzle 16, the material 12 entering the cylinder 11b and goose-neck 11a through a passage 11c. With this construction, the material 12 may be forced under pressure into the mold chamber 18 of two die parts 19, 19a.

The die parts 19, 19a are movable toward and from each other by suitable means forming no part of this invention, and upon one edge portion of a mounting tape or strand 20 disposed between the die parts, the latter entering the lower chamber 18 of the die parts to facilitate the molding or casting of the link or element 21 on that part of the strip 20 disposed within the

mold chamber 18. At 22 is shown a core member which is positioned between the die parts 19, 19a and enters the mold chamber 18 so that the link or element 21 is molded or cast thereon.

5 A core member 22 forms a means for permitting the ejection of the cast or molded element 21 from the die parts when separated as is indicated in Fig. 4 of the drawings and also as a means for feeding the formed element 21 including the mounting strip 20 so as to properly space the elements 21 one with respect to the other on the strip 20, the core being removed from the formed element by upward movement of the core when the element engages the lower surfaces 19b of the die parts as indicated in Figs. 5 and 7 of the drawings and also represented in Fig. 6 of the drawings. As will be seen in Fig. 1 of the drawings, a heating element 23 of the electrical type is disposed on the nozzle 16 to maintain the proper temperature to said nozzle to avoid any possible congestion of the material 12 therein. A rheostat or other control 23a is in circuit with the element 23 to control the temperature thereof.

25 At 24 is indicated a shearing or trimming blade which is adapted to trim off the gate 21a of the links or elements 21 when the same are positioned beneath the die parts 19, 19a as indicated in Fig. 8 of the drawings. At this time, 30 it will be understood that the dies 19, 19a or the mold chamber 18 thereof are of such contour as to form on the links projecting knobs or beads 21b at one side thereof, whereas the other die part or core member 22 forms at the opposite side of each link a recess 21c, note Fig. 8 35 of the drawings, the latter receiving the bead or knob 21b of an opposed stringer in coupling the strings together as is common in other devices of this class.

40 It is also preferred that the mold chamber 18 be so fashioned as to produce rounded edges or corners to the resulting links as is clearly illustrated in the drawings, and it will also be apparent that any design or ornamentation may 45 be applied to the links for purposes of characterization and any form of projecting members and recesses forming the interlocking portions of the elements may be provided. At this time, it is also well to bear in mind that in casting 50 the links on the mounting member 20 and when the latter is composed of fibrous material, the casting or molding material employed will penetrate the interstices of the tape or member 20 securely supporting the same thereon and 55 against displacement therefrom.

55 It will appear from the drawings that the outer surface 16a of the nozzle 16 is flat and sufficiently wide to at all times engage the surfaces of the die parts 19, 19a, note Fig. 4 of the drawings, and a plunger 25 actuated by a spring 26, note Fig. 1, serves to at all times support the nozzle 16 in engagement with the die parts, it being understood that the entire casing 10 is free to move in its support, it being understood 60 that the tension of the spring 26 will be sufficient to maintain the surface 16a of the nozzle in firm engagement with the die parts in the casting operation to avoid any possible flash between such surfaces.

65 70 In Fig. 2 of the drawings, I have shown a slight modification which deals solely with the construction of the container for the casting of molding material and the method of injecting the same into the mold chamber of the die.

75 In this figure, 27 represents a pot or container

having a gooseneck discharge 27a similar in all respects to the discharge 11a, and substituted for the cylinder 11b is a large cylinder or pressure chamber 27b having a removable cap 28 controlling the admission of the casting or molding material 29 into the chamber 27b, the cap 28 being preferably retained against displacement by a pressure screw 30 supported in a hook-shaped bracket 31. Communicating with the upper end of the chamber 27b is a pipe 10 32 which extends to and is in communication with a pressure chamber 33 through a passage 34. A plunger or piston 35 is mounted to reciprocate in the chamber 33, the latter having a bore 36 at one side thereof for admitting and 15 exhausting air with respect to the chamber 33.

In the operation of this form of construction, when it is desired to discharge the material 29 from the pot 27 through the nozzle 16 and into the mold chamber 18 of the die parts, the piston or plunger 35 is moved downwardly as seen in Fig. 2 of the drawings to compress the air in the chamber 33 as well as the chamber 27b sufficiently to force the material 29 into the mold chamber 18, it being understood that the 25 respective areas of the chambers 33 and 27b and the method of actuating the plunger 35 will be designed to satisfy the pressure requirements for the different types and kinds of casting materials employed as well as to satisfy the requirements of the particular casting to be formed thereby. The other elements of the construction shown in Fig. 2 of the drawings are similar to those shown in Fig. 1, and like references will represent like parts.

35 The die parts 19, 19a are made hollow in Fig. 3 of the drawings or have water circulating chambers 37 therein with which communicate intake pipes 38 and exhaust pipes 39. In Figs. 1 and 2 of the drawings, I have indicated at 40 40 the feed drum for feeding the mounting strip or tape 20 to space one set of the links 21 from another set thereof to form the spacing indicated at x, note Fig. 9 of the drawings. In this connection, it will also be noted that suitable gripping or friction means 41 is also employed, note Fig. 1, to support the tape 20 after the core 22 has been removed from the forming link while the die parts are still in 45 open position.

50 The method of producing fasteners of the type under consideration will be readily understood from the diagrammatic illustration of the machine elements disclosed and the following statement. After the casting or molding material 55 12, 29 is heated to the desired temperature, a mounting strip or strand 20 is supported between adjacent surfaces of the die parts 19, 19a, in such position as to enter recesses 20a in the die parts and so as to dispose the beaded or 60 enlarged edge 20b of the strip 20 and an adjacent portion thereof within the mold chamber 18 formed between the die parts, it being understood that the nozzle 16 is always in abutting engagement with the die parts 19 even in their 65 separated position as indicated in Fig. 4. The die parts are now brought together into firm engagement with each other and with that part of the strip 20 disposed therebetween and with the core 22 which also extends into the mold 70 chamber 18. When in this position, the casting material 12, 29 is forced by a suitable pressure element into the mold chamber 18 to form one of the links 21 upon the beaded edge 20b of the strip 20 and upon that portion of the core 7

22 disposed within the mold chamber 18. The die parts are now separated, the core acting as means for ejecting the cast or molded link 21 from the die parts and also as a means for supporting and feeding the formed link.

5 The next step consists in moving the core including the formed link downwardly into the position indicated in Fig. 5, after which the die parts 19, 19a are brought together to a slight 10 extent as indicated in Fig. 6, with the lower surfaces of said parts upon the upper surface of the link as viewed in Fig. 7, and the core 22 is now removed from the formed link 21 by upward movement thereof in the manner indicated 15 in Fig. 7, leaving the link 21 released from the core in a definitely spaced relation with respect to the mold chamber 18 of the die parts to accurately space the links 21 longitudinally of the tape 20. The die parts 19, 19a are again re- 20 turned to the closed position indicated in Figs. 1, 2 and 3 of the drawings, and another or next adjacent link is cast in the manner above set out. In this operation, the gate 21a of the previously 25 formed link is severed by the knife or trimming tool 24 in the manner indicated in Fig. 8 of the drawings.

These operations continue until a predetermined number of links are disposed upon the edge of the tape to define a definite or predetermined stringer length after which a suitable feed wheel 40 is brought into operation to feed the tape 20 so as to provide a wide spacing on the tape as at x, Fig. 9, to space the stringer lengths or groups one from the other whereby 35 the strip 20 may be served intermediate the groups to form the independent stringers as will be apparent.

In the above operations of casting the links upon the tape or mounting strip 20, it will be understood that when this strip is composed 40 of fibrous or similar material, the molding or casting material will penetrate through or into the fibres or through the interstices of the braid when a braided or woven tape is employed 45 to securely retain and anchor the links thereon. It will also be understood that during the steps of casting or molding the links upon the tape, water or other cooling fluid is circulated through the die parts 19, 19a by introduction through 50 the pipes 38 and immediately discharged through the pipes 39, the latter being located adjacent the mold chambers as is also the chambers 37 for the circulating agent. This will prevent 55 any possible overheating of the dies, and will also eliminate any tendency of burning or char- 60 ring the mounting strip 20, especially when composed of fibrous material.

In this connection, it will also be apparent that at no time does the strip 20 remain between the die parts for any appreciable length of time, and it is also a well known fact that the heat of the casting material will be immediately absorbed by the metal die parts 19, 19a. However, should the temperature of the casting or 65 molding material employed be excessively high, the strip 20 may be treated with a fire or flame proofing compound to avoid any possible injury thereto.

It is within the scope of the method herein 70 disclosed that different types of casting or molding materials may be employed, such for example, as various kinds and classes of metals or metal alloys which would be suitable for the purpose herein intended, and which will depend to some degree upon the type or character

of the mounting strip or member employed, and at the same time, it will appear that thermoplastics capable of being molded or cast in accordance with the method herein set forth can also be employed.

5 It will be apparent that the invention is not necessarily limited to the specific form of coupling links herein disclosed, nor in fact to the formation of the particular type and kind of devices herein illustrated, and various other 10 changes in and modifications of the method herein disclosed may be made within the scope of the appended claims without departing from the spirit of the invention or sacrificing its advantages.

15 Having fully described our invention, what we claim as new and desire to secure by Letters Patent, is:

1. The herein described method of forming separable fasteners which consists in arranging 20 a core member and mounting strip between adjacent surfaces of opposed die parts with portions of said member and strip within the mold chamber thereof and in spaced relation to each other, supporting a discharge nozzle in 25 engagement with the die parts, discharging molding material through said nozzle and a passage arranged between the die parts into the mold chamber under the action of a pressure element to form a coupling element on that 30 part of the strip and core within the chamber of said die parts with a gate on said coupling element formed by said passage, and feeding the formed coupling element and strip by said core member to position said strip for the next successive 35 element to be formed thereon and then removing the core from said element.

2. The herein described method of forming separable fasteners which consists in arranging 40 a core member and mounting strip between adjacent surfaces of opposed die parts with portions of said member and strip within the mold chamber thereof and in spaced relation to each other, supporting a discharge nozzle in engagement with the die parts, discharging molding 45 material through said nozzle and a passage arranged between the die parts into the mold chamber under the action of a pressure element to form a coupling element on that part of the strip and core within the chamber of said 50 die parts with a gate on said coupling element formed by said passage, feeding the formed coupling element and strip by said core member to position said strip for the next successive element to be formed thereon, then removing the 55 core from said element, and then trimming the coupling element to remove the gate therefrom.

3. The herein described method of forming separable fasteners which consists in arranging 60 a core member and mounting strip between adjacent surfaces of opposed die parts with portions of said member and strip within the mold chamber thereof and in spaced relation to each other, supporting a discharge nozzle in engagement with the die parts, discharging molding 65 material through said nozzle and a passage arranged between the die parts into the mold chamber under the action of a pressure element to form a coupling element on that part of the strip and core within the chamber of said die 70 parts with a gate on said coupling element formed by said passage, feeding the formed coupling element and strip by said core member to position said strip for the next successive 75 element to be formed thereon, then removing

the core from said element, then trimming the coupling element to remove the gate therefrom, and circulating cooling fluid into and through the die parts with the discharge of the fluid arranged adjacent the mold chamber thereof.

5. The herein described method of forming separable fasteners which consists in arranging a core member and mounting strip between adjacent surfaces of opposed die parts with portions of said member and strip within the mold chamber thereof and in spaced relation to each other, supporting a discharge nozzle in engagement with the die parts, discharging molding material through said nozzle and a passage arranged between the die parts into the mold chamber under the action of a pressure element to form a coupling element on that part of the strip and core within the chamber of said die parts with a gate on said coupling element formed by said passage, feeding the formed coupling element and strip by said core member to position said strip for the next successive element to be formed thereon, then removing the core from said element, then trimming the coupling element to remove the gate therefrom, circulating cooling fluid into and through the die parts with the discharge of the fluid arranged adjacent the mold chamber thereof, and intermittently feeding the mounting strip to space the coupling elements in groups thereon to form predetermined stringer lengths.

5. The herein described method of forming separable fasteners which consists in arranging a core member and mounting strip between adjacent surfaces of opposed die parts with portions of said member and strip within the mold chamber thereof and in spaced relation to each other, supporting a discharge nozzle in engagement with the die parts, discharging molding material through said nozzle and a passage arranged between the die parts into the mold chamber under the action of a pressure element to form a coupling element on that part of the strip and core within the chamber of said die parts with a gate on said coupling element formed by said passage, feeding the formed coupling element and strip by said core member to position said strip for the next successive element to be formed thereon, then removing the core from said element, then trimming the coupling element to remove the gate therefrom, circulating cooling fluid into and through the die parts with the discharge of the fluid arranged adjacent the mold chamber thereof, heating the molding material and said nozzle, and automatically controlling the temperature of said molding material.

6. The method of manufacturing separable fastener devices having a plurality of coupling elements arranged and spaced longitudinally of one edge of a supporting body which comprises moving single impression dies for successively molding each of the coupling elements toward and from each other and opposed sides of said body and a core member disposed therebetween with the body and core member arranged in spaced relation with respect to each other in said dies, supporting a discharge nozzle under pressure in constant engagement with said dies and then discharging heated molding material under pressure from said nozzle into the dies to form therein a coupling element disposed on said body and member.

7. The method of manufacturing separable

fastener devices having a plurality of coupling elements arranged and spaced longitudinally of one edge of a supporting body which comprises moving single impression dies for successively molding each of the coupling elements toward and from each other and opposed sides of said body and a core member disposed therebetween with the body and core member arranged in spaced relation with respect to each other in said dies, supporting a discharge nozzle under pressure in constant engagement with said dies and then discharging heated molding material under pressure from said nozzle into the dies to form therein a coupling element disposed on said body and member, heating the molding material in a supply receptacle and in its passage through said nozzle, and circulating a cooling agent through the dies adjacent the coupling element formed therein.

8. The method of manufacturing separable fastener devices having a plurality of coupling elements arranged and spaced longitudinally of one edge of a supporting body which comprises moving single impression dies for successively molding each of the coupling elements toward and from each other and opposed sides of said body and a core member disposed therebetween with the body and core member arranged in spaced relation with respect to each other in said dies, supporting a discharge nozzle under pressure in constant engagement with said dies and then discharging heated molding material under pressure from said nozzle into the dies to form therein a coupling element disposed on said body and member, and intermittently feeding said body to space the coupling elements in groups thereon.

9. The method of manufacturing a fastener device comprising an elongated supporting body having a plurality of coupling elements arranged and spaced longitudinally of one edge of said body with the coupling parts of said elements protruding beyond said edge, which consists in moving dies for successively molding each of the coupling elements toward and from opposite sides of said supporting body, a forming member disposed therebetween with portions of said member and body arranged within the mold chamber of the dies, supporting a discharge nozzle for the molding material under pressure in engagement with outer surfaces of the dies, then injecting molding material through said nozzle into the mold chamber of the dies to form therein a coupling element disposed on said body and member, separating the dies to eject the coupling element therefrom by said forming member and utilizing said forming member as a feeding and spacing means for intermittently spacing the supporting body to receive a successive series of coupling elements.

10. The method of manufacturing a fastener device comprising an elongated supporting body having a plurality of coupling elements arranged and spaced longitudinally of one edge of said body with the coupling parts of said elements protruding beyond said edge, which consists in moving dies for successively molding each of the coupling elements toward and from opposite sides of said supporting body, a forming member disposed therebetween with portions of said member and body arranged within the mold chamber of the dies, supporting a discharge nozzle for the molding material under

- pressure in engagement with outer surfaces of the dies, then injecting molding material through said nozzle into the mold chamber of the dies to form therein a coupling element disposed on said body and member, separating the dies to eject the coupling element therefrom by said forming member and utilizing said forming member as a feeding and spacing means for intermittently spacing the supporting body to receive a successive series of coupling elements, the formed coupling elements including gate portions, and severing the gate portions from said elements to produce finished elements on said body.
11. The method of manufacturing a fastener device comprising an elongated supporting body having a plurality of coupling elements arranged and spaced longitudinally of one edge of said body with the coupling parts of said elements protruding beyond said edge, which comprises moving dies for successively molding each of the coupling elements toward and from opposite sides of said supporting body, a form member disposed therebetween with portions of said member and body arranged within the mold chamber of the dies, pressure feeding heated molding material into the mold chamber of the dies while maintaining said dies in abutting relation under pressure, introducing a cooling agent into the dies at a point adjacent the mold chamber and immediately ejecting said cooling agent laterally through the dies adjacent said mold chamber.
12. The method of manufacturing a fastener device comprising an elongated supporting body having a plurality of coupling elements arranged and spaced longitudinally of one edge of said body with the coupling parts of said elements protruding beyond said edge, which comprises moving dies for successively molding each of the coupling elements toward and from opposite sides of said supporting body, a form member disposed therebetween with portions of said member and body arranged within the mold chamber of the dies, pressure feeding heated molding material into the mold chamber of the dies while maintaining said dies in abutting relation under pressure to form on said body a coupling element including a gate portion, moving the formed coupling element out of alignment with the mold chamber of the die, and severing the gate from the formed element to produce on said body a finished coupling element.
13. The herein described method of forming a successive series of independent castings on one edge portion of a mounting body, which comprises moving die parts toward and from opposed sides of said body, supporting said dies firmly in abutting relation to each other and to said body with a portion of said body disposed within the mold chamber of said dies, injecting heated casting material into the mold chamber of the dies under pressure to form on that part of the body within said mold chamber a casting including a gate portion, separating the dies to eject the casting therefrom, then feeding the casting and said body transversely with respect to the movement of the dies to position another portion of the body between the dies to receive the next successive casting, and trimming the gate from the casting to form a finished element on said body.
14. The herein described method of forming a successive series of independent castings on one edge portion of a mounting body, which comprises moving die parts toward and from opposed sides of said body, supporting said dies firmly in abutting relation to each other and to said body with a portion of said body disposed within the mold chamber of said dies, injecting heated casting material into the mold chamber of the dies under pressure to form on that part of the body within said mold chamber a casting including a gate portion, separating the dies to eject the casting therefrom, then feeding the casting and said body transversely with respect to the movement of the dies to position another portion of the body between the dies to receive the next successive casting, and trimming the gate from the casting to form a finished element on said body.
15. The herein described method of forming a successive series of independent castings which consists in moving die parts toward and from each other and a core member disposed therebetween and extending partially into the impression formed between abutting surfaces of the die parts, supporting the die parts in closed position under pressure, firmly supporting a nozzle in constant engagement with the dies, introducing heated molding material under pressure into the mold chamber of the dies through said nozzle to form a single casting on said core, separating the die parts to leave the casting supported on the core, and then moving the core to feed the casting out of alignment with the dies and to eject the casting from said core.
16. The herein described method of forming a successive series of independent castings which consists in moving die parts toward and from each other and a core member disposed therebetween and extending partially into the impression formed between abutting surfaces of the die parts, supporting the die parts in closed position under pressure, firmly supporting a nozzle in constant engagement with the dies, introducing heated molding material under pressure into the mold chamber of the dies through said nozzle to form a single casting on said core, separating the die parts to leave the casting supported on the core, then moving the core to feed the casting out of alignment with the dies and to eject the casting from said core, each casting including a gate portion and trimming the casting to remove the gate portion therefrom.
17. The herein described method of forming a successive series of independent castings in spaced relation longitudinally of a mounting member which comprises moving die parts toward and from each other and relatively to said member to dispose a part of said member within the mold chamber of the dies, supporting said dies in closed position under pressure, firmly supporting a nozzle in constant engagement with the dies, introducing heated molding material under pressure into the mold chamber of said dies through said nozzle, electrically heating the molding material and automatically maintaining a substantially fixed temperature to said material by electrically controlled means.
18. The herein described method of forming a successive series of independent castings in

spaced relation longitudinally of a mounting member which comprises moving die parts toward and from each other and relatively to said member to dispose a part of said member within the mold chamber of the dies, supporting said dies in closed position under pressure, firmly supporting a nozzle in constant engagement with the dies, introducing heated molding material under pressure into the mold chamber of said dies through said nozzle, electrically

heating the molding material and automatically maintaining a substantially fixed temperature to said material by electrically controlled means, independently heating the nozzle to maintain the molding material therein in fluid condition, and introducing a cooling agent into the dies and discharging the same laterally through the dies adjacent the mold chamber therein.

LOUIS H. MORIN.

DAVIS MARINSKY. 10
